(57) **CLAIM**

We claim the ornamental design for a frenulum exercising tool, as shown and described.

DESCRIPTION

FIG. 1 is a top perspective view of a frenulum exercising tool showing my new design;

FIG. 2 is a bottom perspective view thereof;

FIG. 3 is a top view thereof;

FIG. 4 is a front view thereof;

FIG. 5 is a left view thereof;

FIG. 6 is a right view thereof; and,

FIG. 7 is a bottom view thereof.

The rear view is a mirror image of the front view.
